[57] **CLAIM**

The ornamental design for a portable instructional display device for welding or the like, as shown and described.

DESCRIPTION

FIG. 1 is an enlarged top perspective view of a portable instructional display device for welding or the like, showing our new design:

FIG. 2 is a top plan view thereof;

FIG. 3 is a right side elevational view thereof;

FIG. 4 is a rear side elevational view thereof;

FIG. 5 is a front elevational view thereof;

FIG. 6 is a bottom plan view thereof; and

FIG. 7 is a left side elevational view thereof. The broken lines shown in FIGS. 1 and 2 are for illustrative purposes only and form no part of the claimed design.
